UNITED STATES PATENT OFFICE

2,495,977

GUNSTOCK AMMUNITION CONTAINER

Jay R. Madsen, Mount Pleasant, Utah

Application April 23, 1946, Serial No. 664,198

7 Claims. (Cl. 42—71)

1

This invention relates to a gunstock ammunition container, and more particularly to such a container that is adapted for use in connection with small caliber rifles.

Among the principal objects of the invention are to provide:

(a) A convenient and safe gunstock ammunition container that is accessible from a side face of the gunstock.

(b) A device that in no way interferes with the ordinary use of a firearm to which it is applied.

(c) A device that keeps ammunition always at hand and in readiness for use.

(d) A device that is self-contained in a gunstock and that in no way detracts from the appearance thereof.

(e) A device which can be easily and quickly applied to existing gunstocks or that may constitute original equipment.

(f) Means for holding original ammunition packages under a slight tension so there is no rattling nor bumping because of lost motion.

(g) A device that is accessible from one side face of the stock, but does not interfere with resting the stock against the cheek of the user in the usual manner.

According to the invention, a recess of preferably rectangular configuration is formed in the stock, the entry aperture of the recess being on the side of the stock which is opposite a user's cheek. In other words, the plane of the entry aperture is substantially vertical when the firearm with its stock is held in the normal firing position. A unique feature is to so arrange the recess that a wall of substantial thickness subsists between the back surface of the recess and the cheek. This recess accommodates a chambered insert which in turn accommodates the length of an ammunition package under at least a fair degree of tension. The breadth of the package is largely accommodated within the thickness of the stock, leaving however, a certain excess of the breadth protruding beyond the side surface of the stock so the package can be easily grasped for removal. Moreover, a suitably fastened cover can be snapped over the protruding portion, the cover being normally fastened in place to press against the protruding portion, all of which contributes to holding the package securely in place. This construction is unique in that it provides the desired storage space without cutting excessively into the stock and at the same time makes it easy for the user to grasp the package.

In the accompanying drawing which illustrates one embodiment of the invention,

2

Fig. 1 represents a side elevation of the butt of a gunstock viewed from the apertured side of the device of the invention;

Fig. 2, a bottom plan corresponding to Fig. 1;

Fig. 3, a vertical section taken on the line 3—3 in Fig. 1, drawn to an enlarged scale;

Fig. 4, a side elevation with the cover in an open position, a portion of the cover being broken away and the figure being drawn to the same scale as Figs. 1 and 2; and,

Fig. 5, an inside elevation of the cover, viewed as indicated by the arrow 5 in Fig. 3, portions being broken away for convenience, and the scale to which this figure is drawn being substantially the same as that used in Fig. 3.

Referring to the drawing, the numeral 10 denotes the butt of a gunstock, in this instance a 22-caliber rifle. This stock is recessed, the recess preferably having a rectangular configuration as shown in Figs. 3 and 4. Substantially lining this recess is a boxlike casing 12 that is made of any suitable material, for example, metal, plastic, or the like. In this instance the casing has an integral frame 13 which more or less overlaps the side of the stock. Hinged at 14 to the lower part of the frame 13 is a cover 15, this cover being provided with a catch 16 that in turn is engaged by a keeper 17 when the cover is in the clamping position indicated by the dotted lines.

In the present instance the casing 12 has two similar compartments 18; one of which, in this instance, accommodates a package 19 of so-called "long" cartridges, and another a package 20 of so-called "shorts," these packages being of substantially equal length, but varying in height, as indicated in Fig. 4. The compartments 18 and 19 are advantageously separated by a partition 21 preferably, hollow, so as to provide sufficient width between the two packages to admit the mounting of the catch 16 when the cover 15 is in the dotted line position. Obviously, only one compartment 18 might be provided if so desired, it being assumed that any skilled artisan can make requisite changes without a detailed showing thereof herein.

It is to be understood that the dimensions of the compartment 18 are such that a reasonable pressure is necessary to force the packages 19 and 20 into place, leaving however, appreciable portions of the respective packages protruding from the side surface of the stock 10, as indicated in Fig. 3. This provides for a substantial thickness of a wall 22 between the bottom of the recess 11 and the cheek (not shown) of a person

using the firearm. Without the wall 22 an advantage of the invention would be lost.

Assuming that one or the other or both packages 19 and 20 have been inserted in place, the cover 15, which is held in the open position of Figs. 3 and 5 by means of a spring 23, is pushed into the clamping position of the dotted lines in Fig. 3, the catch 16 meanwhile slipping into the opening 24 of the keeper 17. The catch 16 has the integral stem 25 with the collar 26, and is under the pressure of a tension spring 27, the stem 25 being held in a guide clip 28 that is soldered or otherwise fastened to the cover 15. Means for manually pushing the catch 16 out of the engaging position when opening the cover, is provided by a pin 29 having the accessible button 30. The pin 29 moves in a slot 31 and the button 30 is encircled by a protecting guard 32 for the purpose of preventing accidental movement of the button 30.

It should be noticed that the cover 15 is cupped in order to receive the protruding portions of the contained package, and that the aforementioned clamping action is brought about because the inside surface of the cover bears at least partially against the packages 19 and 20 so as to assist in preventing any inadvertent rattling of the packages.

This invention, as illustrated, is intended for a person having a so-called righthand disposition, and it should be understood that a person having a lefthand disposition requires an arrangement in which the various parts would be opposite in hand.

While the present drawing shows only packages of "longs" and "shorts" it is obvious that changes can be made to accommodate the "long rifles," since the height of the package is merely a matter of keeping within the range of the size of the stock.

While specific details of construction are necessarily shown and described herein by way of illustration, the invention is limited only by the terms of the following claims.

What is claimed is:

1. A gunstock comprising a butt having a recess therein, the entry aperture of said recess being in coincidence with one side face of said butt so that the plane of said aperture is substantially vertical when said gunstock is in the normal firing position; a wall portion between the back surface of said recess and the other side face of said butt, and a cover having a cupped configuration that is substantially in registry with said recess so as to complement the storage capacity of the latter.

2. A gunstock comprising a butt having a recess therein, the entry aperture of said recess being substantially in coincidence with one substantially vertical side face of said butt when said gunstock is in the normal firing position; a walled box constituting a lining and cover support for said recess; a downwardly swinging cover attached to said box, said cover having a cupped configuration that is in substantial registry with said entry aperture when the cover is in communication with the entry aperture so as to complement the storage space of said box; and means for fastening the cover in communication with the entry aperture.

3. A gunstock comprising a stock having a rectangular recess therein, said recess having an aperture with a perimeter substantially coincident with one side surface of the stock, said

side surface being substantially vertical in the normal firing position of said gunstock and opposite that side surface which rests against the cheek of a user; a wall portion between the cheek-resting surface and an inner surface of said recess; a cover having a space therein, said cover being hinged to the stock along the lower portion of said perimeter so as to swing downwardly from the vertical position, said cover being adapted to register with said perimeter whereby the space within the cover complements the space of the recess and adapts the combined space to accommodate the depth of a commercial package of ammunition; a self-locking catch operatively disposed in, and transversely of, said cover; and a keeper on the stock above the said recess, said keeper being adapted for engagement by the catch when the cover is in communication with the entry aperture.

4. A gunstock comprising a stock having a recess therein; said recess having its entry aperture coincident with a substantially vertical side face of said stock in the normal firing position, said recess being adapted to partially accommodate the depth of a commercial package of ammunition; a cupped, downwardly swinging, cover which is hinged to the stock, the cupping of the cover being adapted to accommodate the remainder of the commercial package depth whereby the inside surface of said cover is brought to bear against said package when the cover is closed; and means for normally holding said cover positively in the closed position against said package.

5. A gunstock comprising a stock having a recess extending inwardly from one substantially vertical side face of the stock when said gunstock is held in the firing position, said recess having an entry perimeter; a wall portion extending inwardly from the opposing side face of the stock and adapted to provide a limit for the depth of said recess, said depth being appreciably less than the width of a commercial package of ammunition; and a cupped cover adapted to seat along said perimeter and having a depth sufficient, when added to the first-mentioned depth, to closely accommodate the depth of such commercial package; and a frame attached to said stock, said cover being hinged to the frame so as to hold the cover seated along said perimeter.

6. A gunstock comprising a butt having a recess therein, said recess having its entry aperture in coincidence with a substantially vertical side face of said stock when said gunstock is held in the normal firing position, the depth of said recess being appreciably less than the thickness of said stock; a thin-wall, open top casing fitting closely into said recess, said casing having a length along the stock adapted to equal twice the length of a commercial package of ammunition for the gun with a predetermined tolerance; the inside height of said casing being adapted to closely accommodate the height of such a commercial package, and the depth of said casing being appreciably less than the width of said commercial package; a frame flange extending around the open top perimeter of said casing; a cupped, down-swinging cover hinged to the lower member of said frame, the cupping of said cover being of sufficient depth and adapted to bear against a commercial package in said casing when the cover is in closing communication with the open top of said casing; and means opera-

tive to normally hold said cover in closing communication with the open top of said casing.

7. A gunstock according to claim 6, wherein the means for holding cover normally in closing position is a spring-pressed sliding bolt positioned in the hollow of the cover so as to occupy approximately the aforementioned tolerance; and wherein is included a keeper located in the upper portion of the frame, said keeper being in alignment with, and cooperative to engage, said 10 sliding bolt when the cover is closing.
